UNITED STATES PATENT OFFICE.

JOSEPH VIVIER, OF BRUSSELS, BELGIUM.

STRINGING PIANOS.

SPECIFICATION forming part of Letters Patent No. 325,189, dated August 25, 1885.

Application filed November 6, 1884. (No model.) Patented in Belgium May 5, 1884, No. 65,045, and October 30, 1884, No. 66,745 in England October 28, 1884, No. 14,232; in Germany November 3, 1884, No. 32,087, in France November 4, 1884, No. 165,159; in Austria-Hungary November 8, 1884, No. 42,047 and No. 9,870, and in Italy December 10, 1884, No. 17,663.

To all whom it may concern:

Be it known that I, JOSEPH VIVIER, a subject of the King of Belgium, and a resident of Brussels, Belgium, have invented certain Improvements in Pianos, (for which I have obtained patents in Belgium, No. 65, 045, dated May, 5, 1884, and No. 66,745, dated October 30, 1884; in Great Britain, No. 14,232, dated October 28, 1884; in Germany, No. 32,087, dated November 3, 1884; in France, No. 165,159, dated November 4, 1884; in Austria-Hungary, No. 42,047 and No. 9,870, dated November 8, 1884, and in Italy, No. 17,663, dated December 10, 1884,) of which the following is a specification.

My invention relates to devices for stringing pianos of that class in which tension is applied to the strings by the direct action of a screw, instead of the ordinary wrest-pins; and the object of my invention is to construct a cheap and economical form of such a stringing device which may be applied to pianos of ordinary construction.

In the accompanying drawings, Figure 1 is a transverse section of my improved construction. Fig. 2 is a partial front elevation. Fig. 3 is a part of the improvement, viewed from above. Fig. 4 is a plan, drawn, to a larger scale, of the guide-plate constructed for the mode of fastening which it is preferred to employ. Figs. 5 and 6 are transverse sections of the same. Fig. 7 is a plan of a guide plate for another mode of fastening. Figs. 8 and 9 are transverse sections of the same. Figs. 10 and 11 are views and sections of the screws for the first mode of fastening. Figs. 12, 13, and 14 are views and sections of tension screws for the second mode of fastening. Figs. 15 and 16 are a section and an elevation of the tension-nut, and Fig. 17 illustrates the application of the invention to the tension of oblique cords.

The tension screws V are threaded rods having square prolongations or shanks, as illustrated in Figs. 11, 13, and 14, or enlarged prolongations, as indicated in Figs. 10 and 12, but always of the same narrow form, in order to admit of the wires being brought sufficiently near together.

There are two modes of attaching the wires. 50 The first mode (which is preferable) consists, as shown in Figs. 10 and 11, in making two holes in the lower ends of the screws and passing the wire through these holes, causing it to take four turns upon the shank, thus rendering it impossible for the wire to slip from the screw when stretched. The second mode consists in providing in a suitable manner upon the lower extremities of the tension-screws knobs or studs for the reception of eyes or 55 loops formed by bending and twisting the upper ends of the wires, as indicated in Figs. 12, 13, and 14.

The tension-nuts Q, which are applied to the screws for stretching the wires in the manner indicated in Fig. 15, are of a height proportioned to the travel of the screw, and their upper part is fashioned like the head of a wrest-pin, Fig. 16, in order that it may be turned by a suitable key. A small hole is provided at the upper part for the free escape of air which would be compressed by the tension, Fig. 15.

The support, which is of the same length as the key-board, is composed of a supporting- 75 plate, A, to which is connected parallel thereto a guide-plate, B, arranged at a distance determined by the height of distance-pieces C, and corresponding with the extent of motion allowed for the tension-screws. 80

The plate A, the plate B, and the distance-pieces C (which in the example illustrated consist of flat bars) may be connected together by screws or rivets q, passing through the plates and the distance-pieces, Fig. 1. The 85 distance-pieces C may, however, be rolled in one with the supporting-plates, or again may simply consist of short tubes distributed at small intervals between the plates.

The supporting-plate A, of suitable width, is 90 firmly secured to the frame by strong bolts p, and in such manner that the internal distance-piece bears against the frame at the upper edge of a metal plate; D, firmly secured to the latter by screws or by other suitable means 95 immediately above the sounding-board. The plate D carries a projecting bridge, S, and is provided with tapped holes for adjusting the

counter-bridge S' . This plate may be dispensed with, the wood of the frame in this case being made of the requisite form. The supporting-plate is perforated at the part 5 projecting over the bed or frame with three parallel series of holes regularly arranged, which receive the threaded portion of the tension-screws V . This arrangement of the tension screws in three rows is necessary, in order 10 to that the requisite space for the application of a key to the nuts Q may be provided between the latter, Fig. 3. It is on account of this arrangement that the prolongations of the tension-screws in either mode of fastening have 15 to be made alternately wide or simply square, in order that the points of connection with the wires may be brought as nearly as possible into one vertical plane, the prolongations or shanks of the tension-screws being 20 guided in openings corresponding to their sectional form punched out in the guide-plate B , and facing the holes in the supporting-plate or wrest-plank A .

In the case of the first method of fastening 25 and for a note requiring three wires, two wide or flat shanked tension-screws are employed to every square-shanked screw. This arrangement is illustrated in Fig. 4, which shows the three wires a b c attached to their respective 30 tension-screws in the same plane, the distance between each two three-wire notes being only equal to the thickness of a shank. When the second mode of fastening is adopted, one square-shanked screw, a , is employed with two 35 wide shanked screws, b and c , alternating with three square-shanked screws, a' b' c' , as shown in Fig. 7, in which the studs for connecting the wires are shown in dotted lines. This arrangement, although equally good, is less symmetrical. 40

The number of holes in the support or wrest-plank and guide-plate is naturally the same as the number of wires, and decreases with the latter. Thus, for a note to be rendered by two 45 wires, there would only be the holes a and b or a and c , with the corresponding tension-screws, and for notes with one wire the square-shank screw a would be sufficient. The whole 50 of the wires are supported on the bridge or sill S in the usual manner and maintained by the counter-sill S' . The wires are arranged in the piano in the usual manner by hooking the lower ends of the wires over a pin firmly 55 fixed in the wood of the piano and drawing it over the bridge crossing the sound-board; but at the upper end, before the nut is put

over the tension screws to which the upper end of the wire is attached, and which is introduced into the wrest-plank from below—that is to say, through the guide-plate—the slack of the wire should be taken up by means of pinchers, levers, or other suitable devices, in order that there may be no unnecessary work for the nut to do in effecting the desired tension, which is then exerted throughout the 60 whole length of the wire. When all the nuts Q , provided with small washers r , are put on the wrest-plank and present the same appearance as the heads of ordinary wrest-pins, the whole may be covered with a removable 70 sheet-metal case, L , Figs. 1 and 2, in order to protect the whole from dust and damp. All the metal parts are preferably nickel plated, in order to protect them from rust. 75

When the invention is applied to pianos with oblique wires, the same construction is employed, the wires being carried down vertically to a certain suitable point, where one or more guide-pins, F F , Fig. 17, are inserted. In the case of grand pianos, the same construction is employed in a horizontal position, but in such a manner that the wrest-plank shall not impede the movement of the mechanism connected with the keys, and the protecting case L is placed in the front of the piano. 80 85

It will be observed that the above-described construction may be applied to pianos of ordinary construction by dispensing with the wrest-pins and substituting therefor the plate A , guide-plate B , and distance-pieces, together 90 with the clinching screws and nuts.

I claim as my invention—

1. The combination of the frame of a piano and perforated supporting-plate A with a corresponding guide-plate, B , intermediate 95 distance pieces, and tension screws and nuts adapted to said plate A and the guide-plate, substantially as set forth.

2. The combination of the frame of a piano, supporting-plate, and corresponding guide-plate, with tension-screws, to which the wires 100 of the piano are connected, the said screws having square shanks and enlarged shanks alternately, substantially as and for the purpose set forth. 105

In testimony whereof I have signed my name to this specification in the presence of two subscribing witnesses.

JOSEPH VIVIER.
